(57) **CLAIM**

The ornamental design for a robot end effector, as shown and described herein.

DESCRIPTION

FIG. 1 shows a perspective view of the robot end effector showing a new design;

FIG. 2 shows a front view thereof;

FIG. 3 shows a rear view thereof;

FIG. 4 shows a side view thereof;

FIG. 5 shows another side view thereof;

FIG. 6 shows a top view thereof; and,

FIG. 7 shows a bottom view thereof.

In the above drawings the broken lines and the areas within the broken lines form no part of the claimed design.
